WELL FLOW APPARATUS AND SYSTEM

Clarence D. Fletcher, Fort Worth, Tex., assignor
to Merla Tool Corporation, Dallas, Tex., a cor-
poration of Texas

Application July 9, 1948, Serial No. 37,912

13 Claims. (Cl. 103—233)

1

This invention relates to new and useful im-
provements in a well flow apparatus and system.

Various types of well flow apparatus are in
general use for lifting or raising well fluids up-
wardly through a flow conductor or tubing by
means of an auxiliary lifting fluid, such as gas
or air which is introduced into the flow conductor
or tubing from the annular space surrounding
the tubing between said tubing and the outer
well casing. One well known type of apparatus,
normally referred to as a time-cycle intermit-
ting system, employs a valve or valves connected
in the flow conductor for controlling the admis-
sion of the lifting fluid or gas into said con-
ductor to raise the well fluids therein and said
valve or valves are operated intermittently in
accordance with particular well conditions. The
control of the operation of the gas-admission
valve or valves is accomplished by means of a
time cycle device or controller at the surface
which either opens said valves by a mechanical
means or in those instances where the admission
valves are pressure-actuated, functions to admit
pressure into the annulus surrounding the flow
conductor to build up the pressure to a point
capable of operating said valves.

The use of a time-cycle controller has certain
disadvantages in that it actuates the lifting gas-
admitting valve or valves at specific, predeter-
mined time intervals without regard to the col-
umn of well fluid which may or may not be pres-
ent in the flow conductor. Further, when a series
of pressure actuated control valves are employed
in conjunction with a time-controller, it has been
necessary to construct or adjust the valves to
operate at different operating pressures, that is,
each valve operates at a lower pressure than the
valve thereabove which places the lowest pres-
sure operated valve at the bottom or lower end
of the flow conductor. This is disadvantageous
because of the range of gas pressure which is
required at the surface in order to provide suffi-
cient operating pressure in the lower end of the
well bore.

It is, therefore, one object of the present inven-
tion to provide an improved flow apparatus or
system, of the intermitting type, which employs
a series of pressure operated valves for controlling
the admission of a lifting gas into a flow con-
ductor or tubing and which utilizes, in place of
the usual time-cycle controller, a choke at the
surface when the lifting gas is provided from
the sub-surface formations or from a source hav-
ing a fairly constant pressure or which employs
a choke together with a regulator device at the

2

surface when an auxiliary lifting gas is used,
whereby the system is simplified and is more posi-
tive in operation and also whereby said system
functions to accurately inject or introduce the
lifting gas into the flow conductor as needed and
in accordance with the presence of well fluids
within said conductor so that more efficient oper-
ation is attained.

Another object of the invention is to provide
10 an improved well flow apparatus or system,
wherein a pressure regulator at the surface is
utilized to control the admission of pressure into
the annulus surrounding the well fluid conductor
or tubing, within which the pressure-actuated
15 gas-admitting valves are mounted; the use of said
regulator making it possible to load the valves
in such manner that all of said valves have the
same closing pressure, with the opening pressure
of said valves being controlled solely in accord-
20 ance with the back pressure acting thereon from
within the flow tubing which back pressure is a
function of the well fluids within said tubing,
the arrangement varying the operating range or
spread of each valve in accordance with the par-
25 ticular well fluid conditions at the level of that
valve.

Another object of the invention is to provide an
improved well flow system wherein a pressure-
actuated valve is mounted at a predetermined
level in a flow tubing for controlling the admis-
sion of a lifting fluid from the annulus outside
30 of the tubing into the fluid column within said
tubing, together with a regulating device at the
surface for controlling the admission of the lift-
ing fluid to the annulus to maintain a desired
35 pressure of lifting fluid within said annulus,
whereby said annulus is normally loaded with
a predetermined pressure; opening of said valve
being effected automatically when the back pres-
40 sure on said valve which is caused by the fluid
column rising in said flow conductor reaches a
predetermined point, whereby the lifting gas is
admitted from the annulus when a predetermined
45 fluid column is present in the flow conductor;
closing of said valve resulting when the annulus
pressure is reduced below the predetermined clos-
ing pressure for which the valve is adjusted.

Still another object of the invention is to pro-
50 vide a well flow system, of the character de-
scribed, wherein the regulator at the surface is
set to open to admit additional lifting gas into
the annulus at a pressure which is above the
pressure at which the gas-admitting valve in the
flow conductor will close, whereby additional lift-
ing gas is introduced into said annulus while gas

is still flowing into the flow conductor for lifting purposes; there being a restricting means or choke associated with the regulator, so that the volume of gas being admitted into said annulus is less than the volume of gas flowing from said annulus through the gas-admitting valve and into the flow conductor, whereby even though additional gas is being introduced into the annulus, the annulus pressure may be reduced to the closing pressure of the valve to shut off further admission of lifting gas into the conductor until the next subsequent operation of said valve, said regulator being set to automatically close when a predetermined pressure is attained in the annulus.

A further object of the invention is to provide an improved well flow apparatus including a valve constructed so that it has a fixed closing pressure, that is, said valve will close when a predetermined pressure is present in the annulus outside the flow conductor; the valve being exposed to the back pressure which is present in the flow conductor or tubing, whereby as this back pressure varies the pressure at which the valve opens varies so that actually the operating range or spread of said valve, that is, the range between closing and opening pressures is directly proportional to the back pressure on said valve.

The construction designed to carry out the invention will be hereinafter described together with other features of the invention.

The invention will be more readily understood from a reading of the following specification and by reference to the accompanying drawing, wherein an example of the invention is shown, and wherein:

Figure 1 is a view partly in section and partly in elevation of an improved well flow apparatus or system constructed in accordance with the invention, and

Figure 2 is a transverse, vertical, sectional view of one of the flow or gas-admitting valves of the apparatus.

In the drawings, the numeral 10 designates a well bore through which the usual well casing 11 extends. The usual casing head 12 is mounted at the upper end of the casing at the surface and a well tubing or flow conductor 13 extends axially through the casing and has its upper end projecting outwardly through the casing head. The invention will be described as operating with an auxiliary lifting gas furnished from a suitable source and in such event, a well packer 14 of any desired construction and which is shown schematically surrounds the tubing near its lower end, functioning to pack off the annulus A between the tubing and the casing. The well tubing or flow conductor has the usual inlet ports 15 in its extreme lower end below the packer, whereby the well fluids from the formation may enter and flow upwardly within the tubing or conductor 13.

A lifting fluid, which will be referred to herein as a lifting gas although it may be air or other fluid, is adapted to be conducted into the upper end of the annulus A through an inlet pipe 16 which is connected within an inlet opening 17 provided in the casing head 12. A motor operated valve 18 is connected in the inlet line 16 and its opening and closing is controlled by a pressure controlled regulator 19. Although the regulator may be any standard regulator which may be purchased on the open market, it is preferable to employ a pressure control pilot unit 75

which is exceptionally sensitive to controlled pressure and which is adapted to open and close the motor valve in respect to pressure conditions within the annulus A.

5 The regulator is so arranged that when the pressure in the annulus falls below a predetermined pressure, the motor valve opens to admit additional pressure fluid; upon the attainment of a predetermined pressure within the annulus 10 A, the regulator operates to close the valve 18 and shut off the further admission of pressure fluid into said annulus. In order to control the volume of flow of the pressure fluid into the annulus A, a suitable choke 20 is connected in 15 the inlet line 16 and obviously, this choke will limit the volume of admitted pressure fluid when the motor valve 18 is open.

A plurality of flow valves of the intermitter type which are indicated V1, V2, V3 and V4 in 20 Figure 1 of the drawings, are connected in the well tubing or flow conductor 13 at predetermined spaced levels or elevations. The construction of these valves is subject to some variation and said valves are arranged to control the admission of pressure fluid from the annulus 25 A into the well tubing or flow conductor 13. It will be evident that when lifting gas from the annulus is admitted into the well tubing, said gas will function to lift the well fluids within 30 said tubing to the surface. As above stated, the valves V1 to V4 are of the intermitter type and are adapted to operate intermittently or at intervals to inject a "slug" of lifting gas into the liquid column.

35 One type of intermitter valve which has been found adaptable for use in this apparatus is illustrated in Figure 2 and as shown comprises an outer casing which is formed of an upper or pilot valve section B, an intermediate or power bellows section C and a lower or main valve section D. The sections B and C are connected by a coupling 21, while the sections C and D are connected by a similar coupling 22. The pilot valve section B includes a pilot bellows 23 which has its upper end connected to the lower portion of 40 a closure 24 which closes the upper end of said section. The lower end of the power bellows is connected to a pilot valve stem 25 having a pilot valve 26 secured to its lower end. A coil spring 27 surrounding the valve stem 25 has its lower end engaging the valve 26 with its upper end engaging an inwardly directed flange 28a which is formed at the lower end of a guide sleeve or tube 28 within which the pilot bellows 23 is disposed. The spring 27 constantly urges the valve into engagement with a valve seat 29. The valve seat is mounted within the upper end of an axial bore 30 provided in the coupling 21. Inlet openings 31 are formed in the wall of the section B, whereby the lifting gas from the annulus may enter the interior of the section B and may, through the lower end of the bore and radial ports 28b in the wall of the sleeve 28 act upon the pilot bellows 23. The interior of the pilot bellows contains a predetermined volume of liquid to protect the bellows against rupture under excessive pressure.

45 The pressure of the spring 27 controls the pressure at which the pilot valve 26 will open because obviously, the lifting gas present in the annulus A enters the interior of the section B and acts upon the cross-sectional area of the pilot bellows. This lifting fluid pressure must build up sufficiently to overcome the force of the 50 spring to compress the same before the pilot is

opened. As soon as the pilot valve opens the additional area of said pilot valve, which is normally within the seat 29, is immediately exposed to the pressure and the valve is moved to full open position. As the pressure in the annulus A is reduced to a point insufficient to overcome the downward force of the spring 27, said spring overcomes the action of the pressure on the cross-sectional area of the pilot bellows 23 and the pilot valve is closed. It will be obvious that when the pilot valve is in a closed or seated position, the underside of said valve is within the bore 30 and is not exposed to the annulus pressure but where the valve is unseated, this underside area is acted upon by said annulus pressure. Therefore, the opening pressure, that is, the pressure necessary to open the pilot, is greater than the pressure at which the valve closes. This difference in opening and closing pressures will be referred to herein as the range or spread of the valve units V1 to V4.

Within the intermediate section C is a power bellows 32 which has its lower end secured to an extension 22a formed on the coupling 22. The upper end of the power bellows is secured to an enlarged cap 23 which is formed integral with an elongate operating stem 34. The lower portion of the operating stem extends through the axial bore 35 of the coupling 22 and this portion of the stem is hexagonal or angular whereby by-pass passages 36 are formed between the stem and the bore. A radial bleed port 37 extends through the wall of the bellows 32 so that a flow from the bore 35 to the interior of the intermediate section C may occur, such communication between the interior and exterior of the bellows being at a controlled rate in accordance with the size of the port.

The lower end of the operating stem extends into the lower main valve section D and is adapted to engage an axial shank 38 of a main valve member 39. The main valve member is adapted to engage a valve seat 40 formed within the section D when in its upper or raised position. A radial port 41 extending from the bore 42 of the section D communicates with an inlet port 43 formed in the well tubing 13, whereby communication is established between the bore of the lower section D and the interior of the well tubing. An inlet screen 44 or perforated strainer tube is connected to the lower end of the section D and establishes communication between the annulus A and the lower portion of the main valve section D.

It will be evident that with a pressure within the annulus A, such pressure will act against the lower end of the main valve 39 and will maintain the same seated. The pressure in the annulus may also act through the ports 31 in the pilot section B and upon the pilot bellows but presuming that such pressure is insufficient to open the pilot valve, the main valve 39 will remain closed. Any back pressure on the valve, that is, any pressure from within the flow conductor 13 will act through the port 41 and 43 and within the lower section D. This pressure may also flow upwardly past the angular portion of the operating stem 34 and into the interior of the power bellows. Through the bleed port 37 in the bellows, this pressure may equalize exteriorly of the bellows within the bore C' of the intermediate section C and since the section C is in communication with the bore 30 of the coupling 21, the back pressure from the well tubing may act against the cross-sectional area of the pilot valve

26 which is exposed within the valve seat 29. If there is no back pressure within the flow tubing due to the absence of well fluids therein, there will be no pressure acting against the underside of the pilot valve 26 and under such a condition, the pilot valve will remain closed until the pressure within the annulus A is sufficient to overcome the tension or force of the coil spring 27.

For purposes of this description and merely by way of example, it will be presumed that under atmospheric conditions, the closing pressure of the pilot valve 26 is 400 pounds while the opening pressure will be presumed to be 460 pounds. Under this assumption, when the annulus pressure reaches 460 pounds the pilot valve 26 opens and the pressure of the lifting fluid within the annulus acts on the exterior of the power bellows 32 and functions to compress or collapse the bellows, whereby the operating stem 34 is moved downwardly. Because the effective cross-sectional area of the bellows is greater than the effective cross-sectional area of the main valve 39, it will be evident that the main valve will be moved downwardly off of its seat, whereby the lifting fluid pressure may flow past the seat 40 and through ports 41 and 43 into the flow tubing. Just as soon as the annulus pressure falls below the assumed closing pressure of 400 pounds, the pilot valve 26 is closed by the spring 27. The pressure exteriorly of the power bellows 32 is bled off through the bleed port 37 thereby permitting the differential across the main valve 39 to move said valve to its closed position.

It will be evident that any back pressure present within the tubing will act against that cross-sectional area of the pilot valve 26 which is exposed within the valve seat 29 and this back pressure will be added to the lifting fluid pressure which is tending to open the pilot valve. Therefore, with a back pressure present within the flow stream, the opening pressure of the valve is altered and as a specific example it has been found that with a presumed opening pressure of 460 pounds at atmosphere, a back pressure of 100 pounds acting on the pilot will cause the valve to open when the annulus pressure reaches 445 pounds. A back pressure of 200 pounds acting against the pilot will reduce the opening pressure to 432 pounds while a back pressure of 300 pounds will further reduce the opening pressure to 420 pounds. This reduction in the opening pressure is, of course, based on a particular ratio between the area of the pilot valve seat 29 with respect to the effective cross-sectional area of the pilot bellows for obviously by varying the ratio between the area of the valve seat 29, which is the area exposed to back pressure, with respect to the cross-sectional area of the pilot bellows acted upon by the annulus pressure, it is possible to control the pressure which must be attained within the annulus before the pilot valve opens. It is noted that the back pressure affects only the opening pressure because after the valve opens the underside thereof is exposed to the annulus pressure; however, in all cases with the valves constructed identically, the closing pressure will remain the same which as presumed, will be 400 pounds. Therefore, actually the operating range or spread of the valve, that is, the spread between opening and closing pressures varies proportionately to the back pressure acting on the valve. The particular operating range or spread may, as above pointed out, be controlled accurately by varying the ratio between

the diameter of the valve seat and the effective cross-sectional area of the pilot bellows.

In the operation of the apparatus, the valves V1 to V4 will be assumed to have the presumed 400 pounds closing pressure. All of said valves may be constructed with their pilot bellows bearing the same ratio to the pilot valve seat. Under such a situation, the operating range between opening and closing pressures on all valves would be alike under similar back pressure conditions. However, if desired, certain of the valves may have different ratios between the pilot valve seat and the pilot bellows in which event the operating range or spread between opening and closing pressures of each valve under a given back pressure condition would be different than the remaining valves.

At the start of the operation it is presumed that all valves will have some back pressure thereon and lifting fluid is admitted into the annulus through the motor valve 18 and choke 20 for the purpose of unloading the tubing. The lower valves V3 and V4 will have sufficient back pressure thereon due to the liquid load in the tubing whereby these valves remain open during the unloading operation. As soon as the pressure in the annulus builds up to a point sufficient to open the uppermost valve V1, a charge of gas is admitted into the flow tubing and the fluid above this level is lifted to the surface so that the back pressure on this particular valve is substantially nil. Under the presumed conditions, the opening pressure at atmosphere of the valve is 460 pounds while under a 100 pound back pressure the opening pressure is 445 pounds. Therefore, assuming a 100 pound back pressure on valve V1 when the annulus pressure reached 445 pounds the valve opened and as soon as the fluid was lifted to reduce the back pressure, the opening pressure of this valve immediately raised to 460 pounds. Thus, the upper valve becomes inactive and since the next valve below has some back pressure upon it its opening pressure is less than the opening pressure of the uppermost valve. Thus, the valves are operated successively until the working level of the installation is reached. This working level would be at the particular valve where the flowing bottom hole pressure of the well would feed past the valve at a pressure equal to or slightly less than the operating pressure of that valve. In other words, this working level may be found at valve V3 or it may be at valve V4. The remaining valves in the tubing would remain inactive until such time as the back pressure conditions within the tubing changed so as to bring those valves in operation in accordance with the annulus pressure. Any valve or valves below the working level would, of course, remain open but will be inactive so far as controlling the admission of the lifting gas.

The regulator and the choke 20 are important in the operation of the system because it is necessary to control the incoming pressure fluid during the operation of the valve which is functioning at the working level. It will be assumed that the working level is at valve V3 which is operated on a 32 pound spread, that is, the valve will open at 432 pounds and will close at 400 pounds. Under such a condition it is desirable to build the annulus pressure to 432 pounds and the regulator 19 is provided for this purpose. At the time that the annulus is charged to 432 pounds, the well fluids within the tubing and acting on the valve V3 as back pressure are not sufficient to produce a 200 pound back pressure

which is the amount necessary to cause the valve to open. However, as the well fluids continue to build up and finally exert a 200 pound back pressure on said valve, the 432 pounds charged pressure in the annulus becomes sufficient to open the pilot 26 and then open the main valve 29, whereby a charge of lifting gas is introduced into the flow tubing. As the gas is admitted to the tubing to lift the well fluids therein, the annulus pressure is obviously reduced and continues to reduce toward the 400 pounds pressure at which the valve will close. The regulator 19 is so adjusted at the surface that as the annulus pressure decreases to a point close to the 400 pounds closing pressure, as for example at 405 pounds, said regulator functions to open the motor valve 18 and admit additional lifting fluid into the annulus A. The choke is so arranged that its capacity is less than the capacity through the valve V3, with the result that the lifting gas is admitted into the annulus in a volume less than that passing through the valve. Therefore, even though pressure fluid is being admitted into the annulus through the choke, it is not admitted in sufficient volume to prevent a further reduction in the annulus to the 400 pounds closing pressure of the valve. As soon as the closing pressure is reached in the annulus, the valve V3 closes but the regulator continues to hold the inlet valve 18 open until the annulus pressure has again built up to the 432 pounds pressure which will be required to open valve V3 when the fluid column has built up to the required 200 pounds back pressure.

From the foregoing it will be evident that a well flow apparatus is provided which will operate intermittently and automatically without any time controller mechanism such as is usually employed in the intermitting type of systems. It is possible to obtain the maximum well production and to maintain the lowest possible gas-oil ratio because obviously the valve does not open until sufficient fluid accumulates in the flow tubing. The weight of the column of gas from the surface down to the operating valve, subtracted from the closing pressure of the valve provides the surface gauge reading, whereby the location of the operating valve may be determined. By computing the displacement of the gas in the casing annulus according to the opening and closing pressures of the valve and by computing the amount of fluid in the tubing according to the back pressure and fluid gradient, it is possible to ascertain the gas-oil ratio. The use of the regulator and choke at the surface provides a much simpler arrangement than a time-controlled device. It is obvious that any operating range or spread may be given to the valve since it is only necessary to vary the ratio of the pilot valve seat to the power bellows to obtain different operating ranges or spreads.

The bleed port 37 which is provided for bleeding the interior of the power bellows enters into the operation of the device in that it controls the amount of pressure which is obtainable in the power bellows during operation. By changing the size of this bleed port 37 with respect to the size of the pilot seat, it is possible to control or vary the amount of pressure which may be obtained in the power bellows. Thus, it will be seen that the ratio between the pilot seat and the effective cross-sectional area of the pilot bellows is the governing factor in controlling the operating range or spread which the valve will have under particular back pressure conditions.

The ratio between the pilot seat and the power bellows bleed port 37 enters into efficient valve operation, that is, in efficient opening of the main valve 37, following unseating of the pilot valve.

As above pointed out, the particular system permits the use of an ordinary regulator for automatic operation in place of the uncertain time-controlling device at the surface. It also permits all of the valves to be initially arranged so as to have the same closing pressure. Although a particular type of pilot controlled intermitter valve is illustrated, it is noted that any intermitting type of flow device wherein the back pressure within the tubing functions to vary the opening pressure of the valve, may be employed.

The improved apparatus has been illustrated and described as operating in a so-called closed system wherein the well packer 14 seals off the lower end of the annulus A from the sub-surface formations. However, in some cases and under proper conditions, the lifting gas required for purposes of lifting the fluid within the flow conductor may be furnished from the sub-surface formations. In such event the regulator 19 and choke 28 would not be necessary, the upper end of the annulus being shut off by a suitable valve which would remain closed. The valves V1 to V4 would be set at a pressure slightly lower than the pressure that the well was capable of building up in the annulus. When this annulus pressure builds up to the opening pressure of the valve, the back pressure in the flow conductor acting on the valve would cause the same to open. The flow through the valve would be greater in volume than that entering the annulus from the formations and this would allow the annulus pressure to bleed back to the closing pressure of the valve exactly in the manner above described with respect to an auxiliary lifting gas. The valve would obviously stay closed until the casing pressure built back up.

It would also be possible in certain instances to omit the regulator 19 from the system, as shown in the drawings. Where the auxiliary lifting gas is providing from a casing head gas-line plant or from a gas system maintaining a fairly constant gas pressure, the regulator is not necessary. In this case the valves would be set to work from this substantially constant pressure and only the choke would be employed to restrict the volume of incoming gas when one of the valves is opened to lift well fluids through the conductor, as above described.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A well flow apparatus including, a well casting extending within a well bore, a well tubing extending axially through the well casing and having a well fluid inlet in its lower end, means for packing off the annulus between said tubing and casing above the well fluid inlet, a lifting gas inlet line connected with the upper end of the casing, an inlet valve in said line for controlling the admission of lifting gas into the annulus, whereby said annulus may be charged to a predetermined pressure, a regulator actuated in accordance with the annulus pressure for controlling the operation of the inlet valve, and a

pressure-actuated valve connected in the well tubing and having a predetermined fixed closing pressure controlled solely in accordance with the pressure in the annulus with its opening pressure variable and controlled by the back pressure within the flow conductor acting against said valve, said pressure-actuated valve controlling the admission of lifting gas from the annulus into the well tubing to lift the well fluids therein.

5 2. A well flow apparatus as set forth in claim 1, together with a choke means connected in the inlet line for restricting the volume of gas admitted to the annulus to a volume less than 15 volume of lifting gas which flows through the open pressure-actuated valve, whereby the annulus pressure may bleed down to the closing pressure of the pressure-actuated valve before the annulus is recharged to the predetermined higher pressure.

3. A well flow apparatus including, a well casting extending within a well bore, a well tubing extending axially through the well casing and having a well fluid inlet in its lower end, means for packing off the annulus between said tubing and casing above the well fluid inlet, a lifting gas inlet line connected with the upper end of the casing, an inlet valve in said line for controlling the admission of lifting gas into the annulus, 30 whereby said annulus may be charged to a predetermined pressure, a regulator actuated in accordance with the annulus pressure for controlling the operation of the inlet valve, a plurality of pressure-actuated valves connected in the well tubing at various spaced levels or elevations, all of said valves being set to the same closing pressure with the opening pressure of each valve being controlled by the back pressure within the flow conductor at the particular valve level, whereby when the back pressure on any particular valve reaches a predetermined point said valve opens to admit lifting gas from the annulus into the well tubing to lift the well fluids therein, opening of one of the pressure-actuated valves reducing the pressure in the annulus, whereby the regulator opens the inlet valve to admit additional lifting gas into the annulus, and choke means in the inlet line for admitting the additional lifting gas in a volume less than the volume flowing through the open valve whereby the annulus pressure may be first reduced to the fixed closing pressure of the pressure-actuated valve before said annulus is recharged to the predetermined higher pressure.

4. A system for flowing wells including, a liquid conductor extending axially through a well bore and having a liquid inlet in its lower end, means for introducing a lifting gas into the annulus around the conductor, a pressure-actuated valve mounted in the flow conductor for controlling admission of lifting gas into the conductor, said valve having operating means responsive when the valve is open to annulus pressure and preset to close said valve when the lifting gas pressure falls to a predetermined point, said operating means being responsive when the valve is closed to the combined pressure of the well liquid within the conductor and the pressure in the annulus and being set to operate and open the valve when said combined pressures attain a predetermined pressure, and a regulator actuated in accordance with the annulus pressure for controlling said annulus pressure.

5. A well flow apparatus including, a flow con-

11

ductor extending axially through the well bore and having a well fluid inlet at its lower end, means for packing off the annulus between said conductor and the well bore above the well fluid inlet of said conductor, means at the well surface for conducting a lifting gas into the annulus around the flow conductor, whereby said annulus may be charged with a predetermined lifting gas pressure, a pressure-actuated valve including a main valve member and mounted in communication with the flow conductor for controlling the admission of lifting gas from the annulus into the conductor, operating means including a pilot valve which controls application of pressure to the main valve, said pilot valve being movable to one position to shut off pressure from the main valve to thereby close said main valve and being movable to a second position to admit pressure against the main valve member to thereby open said main valve member, the operating means being exposed to the pressure in the annulus and the back pressure in the flow conductor when in its first position whereby movement of said means and its pilot valve from the first position to open the main valve member is effected by the combined pressures in the annulus and flow conductor, said operating means being exposed only to the annulus pressure when in its second position, whereby a predetermined annulus pressure moves the pilot valve from its second position to its first position to effect a closing of the main valve member, and a regulating device in the lifting gas conducting means and actuated in accordance with the lifting gas pressure within the annulus, whereby when the pressure-actuated valve opens to admit lifting fluid into the flow conductor to thereby lower the annulus pressure, said regulating device is actuated to admit additional lifting gas into the annulus.

6. A well flow apparatus including, a flow conductor extending axially through the well bore and having a well fluid inlet at its lower end, means for packing off the annulus between said conductor and the well bore above the well fluid inlet of said conductor, means at the well surface for conducting a lifting gas into the annulus around the flow conductor, whereby said annulus may be charged with a predetermined lifting gas pressure, a pressure-actuated valve including a main valve member and mounted in communication with the flow conductor for controlling the admission of lifting gas from the annulus into the conductor, operating means including a pilot valve which controls application of pressure to the main valve, said pilot valve being movable to one position to shut off pressure from the main valve to thereby close said main valve and being movable to a second position to admit pressure against the main valve member to thereby open said valve member, the operating means being exposed to the pressure in the annulus and the back pressure in the flow conductor when in its first position whereby movement of said means and its pilot valve from the first position to open the main valve member is effected by the combined pressures in the annulus and flow conductor, said operating means being exposed only to the annulus pressure when in its second position, whereby a predetermined annulus pressure moves the pilot valve from its second position to its first position to effect a closing of the main valve member, a regulating device in the lifting gas conducting means and actuated in accordance with the lifting gas pressure within the annulus, whereby when the pressure-actuated valve opens to admit lifting fluid into the flow conductor to thereby lower the annulus pressure, said regulating device is actuated to admit additional lifting gas into the annulus, and a choke connected in the conducting means for controlling the volume of lifting gas admitted to the annulus, said choke admitting the lifting gas to the annulus at a rate which is less than the rate at which lifting gas flows through the pressure-actuated valve into the flow conductor.

12

the lifting gas pressure within the annulus, whereby when the pressure-actuated valve opens to admit lifting fluid into the flow conductor to thereby lower the annulus pressure, said regulating device is actuated to admit additional lifting gas into the annulus, and means also connected in the conducting means for controlling the rate at which the lifting gas is admitted to the annulus.

10 7. A well flow apparatus including, a flow conductor extending axially through the well bore and having a well fluid inlet at its lower end, means for packing off the annulus between said conductor and the well bore above the well fluid inlet of said conductor, means at the well surface for conducting a lifting gas into the annulus around the flow conductor, whereby said annulus may be charged with a predetermined lifting gas pressure, a pressure-actuated valve including a main valve member and mounted in communication with the flow conductor for controlling the admission of lifting gas from the annulus into the conductor, operating means including a pilot valve which controls application of pressure to the main valve, said pilot valve being movable to one position to shut off pressure from the main valve to thereby close said main valve and being movable to a second position to admit pressure against the main valve member to thereby open said valve member, the operating means being exposed to the pressure in the annulus and the back pressure in the flow conductor when in its first position whereby movement of said means and its pilot valve from the first position to open the main valve member is effected by the combined pressures in the annulus and flow conductor, said operating means being exposed only to the annulus pressure when in its second position, whereby a predetermined annulus pressure moves the pilot valve from its second position to its first position to effect a closing of the main valve member, a regulating device in the lifting gas conducting means and actuated in accordance with the lifting gas pressure within the annulus, whereby when the pressure-actuated valve opens to admit lifting fluid into the flow conductor to thereby lower the annulus pressure, said regulating device is actuated to admit additional lifting gas into the annulus, and a choke connected in the conducting means for controlling the volume of lifting gas admitted to the annulus, said choke admitting the lifting gas to the annulus at a rate which is less than the rate at which lifting gas flows through the pressure-actuated valve into the flow conductor.

8. A well flow apparatus including, a flow conductor extending axially through the well bore and having a well fluid inlet at its lower end, means for packing off the annulus between said conductor and the well bore above the well fluid inlet of said conductor, means at the well surface for conducting a lifting gas into the annulus around the flow conductor, whereby said annulus may be charged with a predetermined lifting gas pressure, and a plurality of pressure-actuated main valves connected in the flow conductor at various spaced levels or elevations, an operating means for each main valve and including a pilot valve for admitting or shutting off pressure to said main valve, each operating means and its pilot valve being actuated to shut off pressure to the main valve when a predetermined pressure is attained in the annulus, said operating means and its valve being actuated to admit pressure to

13

the main valve when a predetermined annulus pressure added to a predetermined pressure within the flow conductor is attained, the operating means of all of said main valves being set for actuation to close the main valve upon the attainment of the same pressure within the annulus, each main valve when opened admitting lifting gas from the annulus into the flow conductors to lift the well fluids therein.

9. A well flow apparatus as set forth in claim 8, together with a regulator mounted in the lifting gas conducting means and actuated in accordance with the lifting gas pressure within the annulus, whereby a reduction in annulus pressure due to opening of any of the pressure-actuated valves to admit lifting fluid into the flow conductor actuates said regulator to admit additional lifting gas into the annulus.

10. A well flow apparatus as set forth in claim 8, together with a regulator mounted in the lifting gas conducting means and actuated in accordance with the lifting gas pressure within the annulus, whereby a reduction in annulus pressure due to opening of any of the pressure-actuated valves to admit lifting fluid into the flow conductor actuates said regulator to admit additional lifting gas into the annulus, and means for admitting the additional lifting gas into the annulus at a rate which is less than the rate of escape of lifting gas through the open pressure-actuated valve, whereby said annulus pressure may be reduced to the closing pressure of said valve before said annulus pressure is again built up to the predetermined pressure to which said annulus is normally charged.

11. A well flow apparatus including, a flow conductor extending axially through the well bore and having a well fluid inlet at its lower end, means for packing off the annulus between said conductor and the well bore above the well fluid inlet of said conductor, means at the well surface for conducting a lifting gas into the annulus around the flow conductor, whereby said annulus may be charged with a predetermined lifting gas pressure, a pressure-actuated valve including a main valve member and mounted in communication with the flow conductor for controlling the admission of lifting gas from the annulus into the conductor, operating means including a pilot valve which controls application of pressure to the main valve, said pilot valve being movable to one position to shut off pressure from the main valve to thereby close said main valve and being movable to a second position to admit pressure against the main valve member to thereby open said main valve member, the operating means being exposed to the pressure in the annulus and the back pressure in the flow conductor when in its first position whereby

14

movement of said means and its pilot valve from the first position to open the main valve member is effected by the combined pressures in the annulus and flow conductor, said operating means being exposed only to the annulus pressure when in its second position, whereby a predetermined annulus pressure moves the pilot valve from its second position to its first position to effect a closing of the main valve member, and means connected in the conducting means for controlling the rate at which the lifting gas is admitting to the annulus.

12. A well flow apparatus as set forth in claim 11, wherein the rate-controlling means is a choke which admits the lifting gas into the annulus at a rate which is less than the rate at which lifting gas flows through the pressure-actuated valve into the flow conductor.

13. A well flow apparatus including, a well casing extending within a well bore, a well tubing extending axially through the well casing and having a well fluid inlet in its lower end, means for packing off the annulus between said tubing and casing above the well fluid inlet, a lifting gas inlet line connected with the upper end of the casing, an inlet valve in said line for controlling the admission of lifting gas into the annulus, whereby said annulus may be charged to a predetermined pressure, a control means for controlling the operation of the inlet valve, a plurality of pressure-actuated valves connected in the well tubing at various spaced levels or elevations, all of said valves being set to the same closing pressure with the opening pressure of each valve being controlled by the back pressure within the flow conductor at the particular valve level, whereby when the back pressure on any particular valve reaches a predetermined point said valve opens to admit lifting gas from the annulus into the well tubing to lift the well fluids therein, opening of one of the pressure-actuated valves reducing the pressure in the annulus, and choke means in the inlet line for controlling the admission of additional lifting gas in a volume less than the volume flowing through the open valve whereby the annulus pressure may be first reduced to the fixed closing pressure of the pressure-actuated valve before said annulus is recharged to the predetermined higher pressure.

CLARENCE D. FLETCHER.
